C. B. LOVELESS.

Gas Retort.

No. 17,435.

Patented June 2, 1857.

UNITED STATES PATENT OFFICE.

C. B. LOVELESS, OF SYRACUSE, NEW YORK.

FEEDING GAS-GENERATORS.

Specification of Letters Patent No. 17,435, dated June 2, 1857.

To all whom it may concern:

Be it known that I, C. B. LOVELESS, of Syracuse, in the county of Onondaga and State of New York, have invented a new and useful Improvement in Gas Apparatus; and I do hereby declare that the following is a full, clear, and exact description of the construction and operation of the same, reference being had to the annexed drawing, forming part of this specification, in which—

Figure 1 is a top view of the rosin chamber and retort. Fig. 2 is a vertical section of the same on α α . Fig. X is an elevation 15 of the apparatus. Fig. Y is a top view of the same. Fig. Z is a sectional view of same.

Similar characters of reference in the several figures denote the same part.

The invention here considered refers to 20 the feeding of rosin to the retort for the generation of gas.

The nature of the invention consists in the combination of certain pipes and a cut off whereby the flow of rosin may be placed 25 directly under the control of the person in charge of the apparatus.

In the drawing A is the stove having inclined flue chute B. Y', purifier consisting of two vessels connected by pipe F, and communicating with retort by pipe D. Pipe E leads to the gasometer. G, gage faucet of the purifier. L, waste faucet. R, retort, communicating with feed chamber H by the two pipes α and β ; the former leading 30 from bottom of feeder to the lower portion of the retort, and the latter extending from the top of retort into the feeder and nearly 35

to the top. The retort is situated within the cylinder of the stove and extends downward as shown in the drawing. The pipe leading from the bottom of the feeder has 40 a conical stopper valve V operated from the top by wheel w , so that its rod r by screwing into the top of the feeder, shall at the will of the person in charge, open or close 45 the said pipe α . By this construction the melted rosin is let to the retort in such quantities as may be desired; the pressure of gas on the top of the contents of chamber H forcing this supply into the retort.

The advantages of the combination aforesaid consist in the facility it gives for filling the supply chamber when the retort is cold, whereby there is no escape of gas from the removal of the rosin vessel for receiving a supply, as is usual in such apparatus. Moreover this construction admits of stopping the generation of gas at any time.

I make no claim to cut off valves broadly considered; but

I claim as new and as an improvement in portable gas apparatus—

The connection of the feeder H with the retort R by the arrangement of pipes α and β when combined with a cut off valve 65 V, the entire arrangement operating substantially as set forth.

In testimony whereof, I have hereunto signed my name before two subscribing witnesses.

C. B. LOVELESS.
